US0D1032507S

(12) **United States Design Patent** (10) **Patent No.:** **US D1,032,507 S**
(45) **Date of Patent:** **** Jun. 25, 2024**

(54) **MAGNETIC CHARGING BASE**

(71) Applicant: **Xiaodong Chen**, Guangdong (CN)

(72) Inventor: **Xiaodong Chen**, Guangdong (CN)

(**) Term: **15 Years**

(21) Appl. No.: **29/922,396**

(22) Filed: **Dec. 21, 2023**

(30) **Foreign Application Priority Data**

Jun. 26, 2023 (CN) 202330393045.X

(51) **LOC (14) Cl.** **13-02**

(52) **U.S. Cl.**

USPC **D13/107**

CLAIM

The ornamental design for a magnetic charging base, as shown and described.

DESCRIPTION

FIG. 1 is a front, top and right-side perspective view of the showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom and left-side perspective view thereof.

The broken lines throughout the drawing figures depict portions of the magnetic charging base that form no part of the claimed design.

1 Claim, 8 Drawing Sheets
